UNITED STATES PATENT OFFICE

2,489,797

APPARATUS FOR MAKING UNDERCUT WARE

William J. Miller, Pittsburgh, Pa., assignor to
Miller Pottery Engineering Company, Swissvale,
Pa., a corporation of Pennsylvania

Original application March 29, 1935, Serial No.
13,683. Divided and this application November
3, 1945, Serial No. 626,456

8 Claims. (Cl. 25—24)

1

This application is a division of my co-pending application Serial No. 13,683 filed March 29, 1935, now Patent No. 2,452,858, November 2, 1948. It has to do with apparatus for making undercut pottery ware.

In the drawings: Figure 1 is a plan view of a portable mold for undercut ware.

Figure 2 is a sectional view taken on the line 2—2 of Figure 1.

Figure 3 is a view in vertical section and side elevation of a mold actuating assembly.

Figure 4 is a horizontal section plan view taken on line 4—4 of Figure 3.

Figure 5 is a view in front elevation of a tool or attachment carriage to which undercutting tools are applied.

Figure 6 is a view of the structure of Figure 5 in side elevation.

Figure 7 is an enlarged sectional view taken on line 7—7 of Figure 5.

Figure 8 is a detail showing a friction drive.

Figures 1 and 2 illustrate a portable mold for undercut ware, by the numeral 59, the mold being formed in sections 59a which are mounted to shift or slide radially on a base 59b, which in turn is mounted to have relative angular shifting or sliding movement with a main base 59c adapted to seat on the rotatable mold-actuating chucks 62 of the machine. Each section is formed with a tangential slot 59d and the base 59b with a corresponding number of arcuate slots 59e, dowels 59f being threaded into the main base 59c and projecting upwardly through both slots into each section 59a. The base 59b is formed with a central boss having a porous insert 59g secured thereon, which forms the bottom of the mold cavity, and guide pins 59h projecting radially therefrom into each section, which serve to guide and accurately position the sections during the opening and closing operations. The chuck is provided with a resiliently-mounted mold-engaging and centering pin 60, see Figures 2 and 3. The base 59c of the mold 59 is recessed at a predetermined point, so that when the rotating chuck elevates to lift the mold from the tray, said pin 60 will register with said recess and effect a positive engagement of the chuck with the mold base. The tray 39 (Figure 2) is also provided with an adjustable, resiliently mounted pin 61 adapted to engage in a bore 59i in the base 59b when the rotating chuck 62 lowers the mold onto the tray. It will be noted that the passages 54n and 54m serve in this instance for admitting sub or superatmosphere to chambers or

2

cavities 59j and 59k, respectively, formed in the porous mold body and base insert 59g.

For opening and closing this form of portable mold, it is preferred to use the chuck assembly described in connection with Figure 3. The parts of this assembly may be adjusted so that the chuck 62 will rise and elevate the mold from the tray and then rotate it clockwise in operative adjacency to the profile to shape the ware, and when the chuck lowers, rotation is stopped at a point which will bring the pin 61 in approximate registration with the bore 59i, the mold then centering on the tray. To open the mold, the chuck 62 is caused to rise and elevate the mold clear of the tray but not clear of the pin 61 and then rotate counter-clockwise, which shifts the locking dowels 59f in the slots 59d and 59e and parts the mold sections to permit removal of the ware. It is preferred to lower the mold onto the tray in open condition, to give ample time for cleaning and drying of the mold sections. Prior to charging the mold with clay, the chuck 62 is again elevated and lifts the mold clear of pin 61 and rotates the mold clockwise to lock the mold sections together.

The mold actuating unit, Figure 3, comprises a casting or frame 63 provided with a bearing housing 63d for a spindle 64, that moves upwardly against the tension of a spring and lowers by gravity assisted by said spring.

The spindle 64 is in spline-sliding engagement with a chuck spindle 62c on which the chuck 62 is secured by a screw 62c' and dowel pin 62c2, reciprocation being imparted to the chuck 62 and spindle 62c by means of a cam 62d, which is adjustably mounted on a cross shaft 62e having bearing in the side frame plates of the main frame of the apparatus, said cam actuating a lever 62f, which is adjustably pivoted at one extremity, the pivoting assembly being supported from the frame 63, and at its opposite extremity pivotally secured to a pitman 62g, the pitman connecting with spindle 62c by means of a cross fork 62h, which is adjustably secured to said pitman by nuts 62i at its one extremity and forked into an annular groove in the spindle 62c at its opposite extremity. The pitman 62g projects through and is guided by extensions 62j of the frame 63, the upper end of said pitman having adjustably threaded therein a contact screw 62k, the function of which will later become apparent.

Rotation may be imparted to the spindle 64 in the unit illustrated in Figure 3 by means of cooperating friction gears 64g and 64h, the gear 64g being adjustably secured on the spindle 64 and

the gear 64h splined for longitudinal sliding movement on a cross shaft 64i, which is preferably continuously driven, this shaft having bearing at opposite extremities in the side frame plates or beams.

The friction gears 64g and 64h are brought into intermittent contact by a lever and brake assembly comprising a brake shoe 64j formed with studs for mounting the shoe for vertical movement on the frame 63, a bell-crank lever 64k pivoted or fulcrumed in said frame, a connecting rod 64l adapted to be adjustably pivoted at one extremity in any one of a plurality of holes formed in said bell crank lever and at its opposite extremity adjustably secured by nuts 64m on a pitman 64n, and cam-contacting arms 64o and 64p which are also adjustably secured on the pitman 64n by nuts 64q and 64r. These arms 64o and 64p are alternately raised and lowered by separate cams, not shown, which are adjustably mounted on the shaft 62e and have a contour substantially similar to the valve cams shown in Figure 4. The frame 63 is formed with guide brackets 64t for the pitman 64n.

To vary the speed of rotation of the chuck during reciprocation thereof, the splined friction gear 64h is provided with a grooved hub 64h', also splined on shaft 64i, and a grooved cam 64h2 is adjustably secured on shaft 62e, motion being transmitted from the cam to said gear by a lever 64h3, which is adjustably pivotally supported at its upper extremity on a bracket extension 63e of the frame 63, said lever extending downwardly, and adjacent cam 64h2 being provided with a pin 64h4 working in the groove of said cam, and at its lower extremity said lever connects with the grooved hub 64h' by a link 64h5 and pin 64h6 working in the groove of said hub.

In operation, the chuck-reciprocating cam 62d and brake cams being adjusted to work in synchronism, when the chuck spindle and chuck elevate, the brake 64j is released, permitting spindle 64 to lower and thus lowering gear 64g into contact with the continuously rotating gear 64h and imparting rotation to the chuck; and when the chuck is lowered, brake 64j is raised and thus contacts with gear 64g and raises the spindle 64, thereby moving gears 64g and 64h on shaft 64i out of contact and stopping rotation of the chuck.

To gradually accelerate and decelerate or vary the speed of rotation of the chuck during reciprocation thereof, the drum cam 64h2 and lever 64h3 may be used to move the gear 64h relatively to gear 64g. Ordinarily, however, the brake, if properly adjusted, will operate to effect gradual contact and release of the gears 64g and 64h and provide for smooth operation of the chuck 62.

Super and sub-atmospheric pressure and other mediums may be applied to the molds through the chuck for various fabricating operations, the passages 62a and 62b (Figure 3) extending down into the chuck spindle 62c as shown, and opening out into annular registering air grooves 62a' and 62b' formed in a hood 70 having a working fit around said spindle and adjustably supported on the frame 63 by a thread rod 70a, hose nipples 62a2 and 62b2 being threaded into the hood 70 and communicating with said grooves. A further communicating passage opening out in the bottom of the chuck is provided by a bore 71 in the screw 62c', the interior of the spindle 62c being hollow, thus forming a chamber 71a, and the hood 70 having a further groove 71b in communication with said chamber, a hose nipple 71c

being threaded into the hood 70 and communicating with said groove. Where the passages 62a, 62b and 71 open out into the chuck 62, resilient sealing and cushioning pads 62t are adjustably threaded into said chuck.

The fabricating tools 80 are mounted on a standard form of carriage assembly substantially similar to that illustrated in Figure 5 and 6, for the purpose of giving them the desired movements relatively to the ware on which they are to perform.

The frame 85a shown as of rectangular shape is mounted to have a vertical sliding fit on posts 85, nuts 85b being threaded on the lower extremities of said posts to adjustably limit the lowermost point of travel of said frame. The frame 85a is formed with a bracket 85c, which is bored to receive a pivot bolt 85d, which is adjustably secured by nut 85d', a lever 85e being pivoted at one extremity in said bolt and at its opposite extremity adjustably and pivotally supported from a post 85f, which also depends from and is secured in the top plate. This lever 85e is provided with a cam roller 85e' adapted for contact 20 with various types of frame-actuating cams shaped in accordance with the work involved and which are mounted on one of the cross shafts 80a, or if the variable speed assembly is used, on the sleeve 68 (Figure 6), these cams being 30 shown in connection with the various attachments hereinafter described.

The lower portion of the frame 85a is formed with a dove-tail slot or groove in which a bar 85g is mounted to have a horizontal sliding fit, the bar at the left as viewed in Figure 5 being formed with a vertical guide bracket 85h having a central slot or track 85h'. A lever 85i provided with a cam roller 85i' is pivotally and adjustably supported at its upper extremity from a post 85j, 40 and at its lower extremity said lever is provided with a pin 85i2 adapted to have a working fit in said track 85h'. As in the case of lever 85e, the cams for the lever 85i are given the required contour in accordance with the work involved and are 45 mounted on one of the cross shafts 80a or sleeve 68, each attachment generally requiring a particular contoured cam which is illustrated in connection with the attachment.

The bar 85g is slotted at 85k, a pin 85k' being secured in the frame 85a, a compression spring 50 85k2 being mounted to abut at opposite ends, respectively, against said pin and the bar 85g. The bar 85g is also provided with a screw bracket 85l in which a contact screw 85m is mounted, which serves to adjustably limit the movement of bar 85g in one direction independently of its cam travel or reverse movement. The screw bracket 85l is adapted to be attached at either end of bar 85g and the spring 85k2 at either end of slot 85k, to conform to the positive direction of movement 60 of the cam lever 85i.

It will be seen that when levers 85e and 85i are oscillated, the frame 85a reciprocates vertically and the bar 85g laterally, the bar deriving its 65 vertical movement from said frame. The frame is provided with screws 85n and 85o adapted to be adjusted in contact with the posts 85 and frame 85a in the event the actuating cams are to be disconnected and the frame and bar set in rigid adjusted position.

An attachment and tool-mounting turret disk 86 is supported from the slide bar 85g by means of a hanger bracket 86a, said bracket being formed with projecting hub portions 86a', and 70 86a2, see Figure 7, and is secured to the bar 85g

by screws 86a3, see Figure 6, the disk 86 being rotatably mounted on the hubs 86a' and prevented from lateral displacement by a ring 86a4. A shaft 86b extends through and has bearing in the projecting hubs of bracket 86a, this shaft functioning in a manner which will later become apparent. The disk may be rotated intermittently in one direction or oscillated, the detents 81g and 81i being housed, respectively, in a gear 86c and the bracket 86a and adapted to register in detent or latch notches 81g' and spotting notches 81i' formed in one side of said disk 86, there being four of each of said notches in the present instance. The gear 86c is mounted to rotate free on the bracket hub 86a' and the teeth 86c' of said gear are in continual mesh with the teeth 86d' of a rack 86d, the latter being slidably dove-tailed into a groove formed in the bracket 86a, see Figure 7, and terminating in a T-head 86d2, see Figure 5 which is formed with a track 86d3. The rack 86d is actuated by a bell-crank lever 86e, which is fulcrumed at 86e' on a bracket extension 86e2 formed on the frame 85a, the one extremity of said lever 86e being provided with a pin 86e3 which has a sliding fit in the groove or track 86d3, while the opposite extremity of said lever has pivoted thereto a connecting rod 86f which extends through a guide bracket 86f3 and terminates in a T-head 86f' formed with a groove or track 86f2, said T-head cooperating with a lever 86g pivotally supported at its upper extremity from a post 86h, which is secured in one of the top frame plates, and at its lower extremity said lever is provided with a pin 86g', having a sliding fit in the groove or track 86f2 of T-head 86f'. Lever 86g is provided with a cam roller 86g2 adapted to contact with a suitably shaped cam to be mounted on shaft 80a, these cams also being generally shown with the respective attachments hereinafter described. A retracting spring 86d4 is secured at opposite extremities, respectively, to the T-head 86d2 and the bar 85g.

A screw 86i is shown as threaded in the bracket 86a, see Figure 7, this screw being adjusted to against the turret disk 86 when it is desired to maintain said disk stationary with said bracket. A screw 86j is also shown threaded in the hub 86a2 of bracket 86a, and this screw may be adjusted against the shaft 86b when it is desired to maintain the latter stationary with said bracket.

The disk 86 is provided with a plurality of holes 86k for attaching various fabricating tools and attachments, such as shaping tools, turning and finishing tools and transfer chucks, which will be described in connection with each respective fabricating operation.

The shaft 86b may be driven by either a positive or friction drive, both forms of drive being shown in Figures 5 and 6 for the purposes of illustration.

A bevel gear 87 formed with a hub 87' is shown as adjustably secured on the shaft 86b, this gear meshing with a similar gear 87a secured on a stub shaft 87a' which has bearing in the projecting extremity of a bracket arm 86a5 formed as part of the bracket 86a. A bracket 87b is adjustably supported by a post 87b' (Figure 6) from one of the top frame plates, and extends down and at its lower extremity is formed with a foot 87b2, a stub shaft 87c having bearing in said foot, this shaft forming part of a flexible coupling comprising a sleeve 87c' and longitudinally grooved

shaft 87c2 in spline-sliding engagement with said sleeve, the lower extremity of shaft 87c2 being coupled for universal movement with the stub shaft 87a' on which gear 87a is secured. The stub shaft 87c of the flexible coupling has adjustably secured thereon a pinion gear 87d. If pinion 87d is used, the drive is effected by means of a segmental gear 87e formed on a lever 87e' which is adjustably pivotally mounted on the bracket 87b and provided with a cam roller 87e2 adapted to contact with a cam to be mounted on shaft 80a or sleeve 68, and which may be given various contours in accordance with the rotation desired for shaft 86b. The lever 87e' may be retracted by a spring 87f.

The profile assemblies 90 are mounted directly on the turret disk 86, there being attachments for four profiles shown, so that four different kinds of undercut ware may be shaped in succession. The profiles are adjustably secured to the disk 86 by slotting the disk and profile at right angles to receive attaching bolts, as at 90d.

The profile 90 for undercut ware, see Figure 2, is provided with a resiliently mounted brim-forming ring 90e having a brim-contacting porous or plaster insert 90f threaded therein, an annular chamber 90g being formed at this point, said chamber being supplied through a duct 90g' and hose nipple 90g2 with a treating medium such as sub or super atmosphere or other fluid. The ring 90e is rotatably mounted in a bearing or supporting ring 90h and held against displacement by pins 90h', so that the ring 90e may rotate with the mold while its supporting ring 90h remains relatively stationary, the hose nipple 90g2 being secured in the ring 90h and the latter formed with an annular groove or chamber in registration with the supply duct 90g'. The ring 90h is secured by threaded pins 90h2 to a bracket 90i, springs 90j being inserted over said latter pins to provide a resilient mounting for the assembly. The bracket 90i is slotted at 90k for the securing pins or bolts for the profile so that the profile and ring assembly have a relative lateral floating association.

It will be noted that the ring 90e centers on the tapered top portions of the sections 59a of the portable mold 59 and clamps or braces the said sections during the profiling operation.

When the profile is removed from the interior of the undercut ware, it is first moved toward the left as viewed in Fig. 2 by cam 85e3, which actuates lever 85i and then elevated by cam 85e2, which actuates lever 85e, while at the same time the mold may be lowered. It will be understood, however, that cam 85e2 could be dispensed with and the molds lowered sufficiently to clear the profile.

The apparatus described herein is employed for the forming or jiggering of pottery articles made from plastic clay wherein the interior of the article is larger in diameter than the mouth such as, for instance, a wide mouth jar having a globular body. The profile 90 is formed with an edged profiling surface shaped to correspond with the vertical contour of the molding surface. It is introduced into the interior of the mold through the mouth thereof and is then moved in a plane perpendicular to the axis of mold rotation a given distance into jiggering position. Upon rotation of the mold, the lower offset portion of the profile tool forms the interior of the globular body portion of the ware and the straight portions of the tool thereabove form the neck or mouth zone 75 of the article.

It will be noted that the profile 90 does not require a trimmer in view of the ring 90e with its brim-contacting insert 90f.

To ensure accurate positioning of the profile relatively to the molds and uniform thickness of the ware, a contact screw 62k' may be adjustably mounted in a bracket 62k2 secured to the turret disk 86, said screw being adjusted to contact with screw 62k threaded into the top of the pitman 62g, Figure 3. When the mold and profile reach their approximate operative positions, the screw 62k and 62k' contact and the profile moves a short distance in unison with the mold.

I claim:

1. In apparatus of the class specified, a mold chuck, means for raising and lowering the chuck, a rotatable turret thereabove, a plurality of profiles formed for making undercut ware mounted on said turret, means for rotating said turret to index the profiles successively with molds therebelow, and means for periodically shifting the turret in a horizontal plane to move each profile to an undercutting position and withdraw the same from said position at the termination of the undercutting operation.

2. In apparatus of the class specified, a mold chuck, means for raising and lowering and rotating the chuck, a partable mold carried by the chuck to be opened and closed incident to movement of the chuck, a rotatable turret above the mold chuck, a plurality of profiles formed for making undercut ware mounted on said turret, means for rotating said turret to index the profiles in succession with molds therebelow, and means for periodically shifting the turret in a horizontal plane to move each tool, when inside a mold, to undercutting position and to withdraw the same from said position at the termination of the undercutting operation.

3. In apparatus of the class specified, a mold chuck, means for raising and lowering and rotating the chuck, a separable mold carried by the chuck, means for opening and closing the mold incident to movement of the chuck, a rotatable turret above said chuck, a plurality of profiles formed for making undercut ware mounted on said turret, means for rotating said turret to index the profiles, in succession, with molds therebelow, and means for periodically shifting the turret in a horizontal plane.

4. In apparatus of the class specified, a separable mold, a mold chuck for supporting said mold in a forming position, means for rotating said chuck and a pin carried by the chuck and engageable with the mold for opening and closing the mold incident to rotation of the chuck, a rotatable turret above said chuck, a plurality of profiles formed for making undercut ware mounted on said turret, means for rotating said turret

to index the tools in succession with molds therebelow, and means for periodically shifting the turret in a horizontal plane to move each profile to an undercutting position.

5. In apparatus of the class specified, a mold formed for making undercut ware, a support for said mold, a rotatable turret above said support, an undercutting profile carried by said turret, means for rotating the turret to index the profile with a mold therebelow, means for shifting the turret in a horizontal plane to move the profile into undercutting position, and means for relatively moving the mold and the profile to perform a jiggering operation.

6. In apparatus of the class specified, a mold formed for making undercut ware, a mold lifter for supporting said mold, a rotatable turret adjacent said lifter, a profile tool formed for making undercut ware mounted on said turret, means for rotating said turret to index the tool with the mold on the lifter, means for shifting the turret in a plane perpendicular to the axis of the lifter to move the profile to an undercutting position, and means for relatively moving the profile and the mold to perform a jiggering operation.

7. In apparatus of the class specified, a mold formed for making undercut ware, a support for said mold, a rotatable turret above said support, an undercutting profile mounted on said turret, means for rotating said turret to index the profile with a mold therebelow, and cam actuated means for shifting the turret in a plane perpendicular to the axis of the mold support to move the tool to an undercutting position.

8. In apparatus of the class specified, a mold formed for making undercut ware, a support for said mold, a rotatable turret above said support, a profile formed for making undercut ware mounted on said turret, means for rotating said turret to index the profile with a mold therebelow, means for rotating said profile, and means for shifting the turret in a plane perpendicular to the axis of the mold support to move the tool to an undercutting position.
